US00D654935S

(12) **United States Design Patent**
Kishimura et al.

(10) **Patent No.:** US D654,935 S
(45) **Date of Patent:** ** Feb. 28, 2012

(54) **INKJET COATER**

(75) Inventors: **Toshiharu Kishimura**, Tokyo (JP); **Naoki Watase**, Tokyo (JP); **Katsuyoshi Watanabe**, Tokyo (JP); **Hideaki Yamamoto**, Tokyo (JP); **Hideo Nakamura**, Tokyo (JP)

(73) Assignee: **Hitachi Plant Technologies, Ltd.**, Tokyo (JP)

(**) Term: **14 Years**

(21) Appl. No.: **29/347,768**

(22) Filed: **May 25, 2010**

(30) **Foreign Application Priority Data**

Nov. 25, 2009 (JP) 2009-027434

(51) **LOC (9) Cl.** **15-09**

(52) **U.S. Cl.** **D15/122**

(58) **Field of Classification Search** D15/122, D15/124, 199; D23/371; 118/64, 300, 309, 118/310, 324

(57) **CLAIM**

The ornamental design for a inkjet coater, as shown and described.

DESCRIPTION

FIG. 1 is a front, top and left side perspective view of an inkjet coater showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines in the drawings depict unclaimed environmental subject matter.
